A. B. Reavis
ATTORNEY

UNITED STATES PATENT OFFICE

CHARLES B. GRAY, OF MILLBOURNE, PENNSYLVANIA

VIOLIN BOW

Application filed June 20, 1929, Serial No. 372,514. Renewed January 7, 1932.

My invention relates to violin bows and it has for an object to provide improved means for connecting the hair band to the frog.

In my Patent No. 1,686,551, October 9, 1928, I disclose and claim twistable connecting means between the hair band and the nut and frog, respectively, such connecting means being twistable so that the band of hair may contact strings flatwise even though the bow may be tilted slightly with respect to the violin strings. Some effort is required to get this accommodation, as it is desirable at times that an edge of the hair band shall bear against a string or strings. Playing of a violin so as to obtain full tonal values requires considerable muscular agility particularly in the wrist, and it is one of the principal objects of the invention of the patent to provide the bow with powers of accommodation to relieve the complexity of muscular movement. It is an object of my present invention to improve the twistable or torsional connection between the hair band and the frog from the points of view of (a) greater strength (b) increased durability (c) the mode of resisting turning of the band (d) manufacture and assembly, and (e) avoiding catching of strings by the torsional or twisting connection particularly on back-strokes. These features of advantage inhere in my improved connection which consists essentially of a tongue connected to the hair band and to the frog together with means for yieldingly resisting turning movement of the tongue. The parts of the connection may be made of suitable metal in order that sufficient strength and durability may be had. As the tongue is elongated in cross section, turning thereof is readily resisted by a spring. The outer end of the tongue is widened to provide a cross bar for the hair band, a suitable clip being provided to clamp the hair band to the cross bar. To prevent catching of string on backstrokes, the connecting device has such surfaces as might otherwise catch inclined. A further object of my invention is to provide a connection having these features of advantage.

My improved connection may be embodied in a frog construction which may be substituted for existing bow frogs; and, to facilitate the application of my improved frog to existing bows, I prefer to make the frog body portion of material, such as rubber, which may be readily rendered partially plastic at the bow stick engaging portion in order that a good fit may be effected. A further object of my invention is to provide for this feature of adaptability.

These and other objects are effected by my invention, as will be apparent from the following description and claims taken in connection with the accompanying drawing, forming a part of this application, in which:

Fig. 1 is a side elevation of a bow having my improvement applied thereto;

Fig. 2 is a plan view from the hair band side;

Fig. 3 is an elevation at the frog end;

Fig. 4 is an enlarged sectional view of my improved frog;

Fig. 5 is a plan view of the apparatus shown in Fig. 4 looking up and with the tongue clip removed;

Fig. 6 is a longitudinal sectional view of the hair band connection assembly;

Figs. 7 and 8 are detail views of the channel member;

Figs. 9 and 10 are detail views of the tongue member;

Figs. 11, 12 and 13 are detail views of the hair band ferrule; and,

Figs. 14 and 15 are detail views of the spring.

Referring now to the drawing more in detail, I show a bow stick 10 and a hair band 11 connected to the nut end 12 and to the frog 13 adjustable in the usual way relatively to the stick.

The frog 13 includes a body portion 14, preferably made of plastic material, having a longitudinal concavity 15 for the stick, this concavity 15 having a metallic liner 16. The body portion is recessed or cored out to receive the hair band connector assembly, at 17, and the tension nut member 18 which cooperates with the bow adjusting screw 19.

The connector assembly 17 consists of a

channel member 20 having a channel 21 for the shank or tongue portion 22 of the tongue member 23 having a widened portion provided with a cross member 24. A lug 25 is provided at the upper side of the tongue member, the lug being engaged over by the portion 26 of the spring 27. The spring is shaped and the channel member is relieved at 28 so that it presses against the upper surface of the tongue or shank portion 22; and, as the latter is elongated in cross section, the spring affords yielding resistance to turning thereof.

The hair band 11 has one end preferably 15 passed under and over the cross portion 24 of the tongue member and a suitable ferrule 30 is pressed or forced thereover to clamp the hair band. In order that the bottom surface 31 may be flush with the bottom surface 20 32 of the channel member (Figs. 2 and 4) the tongue member is bent slightly at 33 to the extent of approximately the thickness of the hair band.

The channel member 20 and the spring 25 27 are connected together in any suitable manner. For example, I show a block or clamp part 35 (Fig. 6) connected or brazed to the channel member 20 and provided with a screw 36 extending through the upper 30 clamp part 37 and having a nut 38 bearing against the part 37. As shown, the spring 27 is of hair pin form with the prongs thereof arranged between clamping parts 35 and 37 and the outer ends are bent up at 39 to bear against the rear face of the clamp part 37. This way of connecting the spring 27 to the channel member is advantageous in that it permits the ready replacement of the spring. The spring is preferably slightly 40 bent at 41 so that it may bear against the upper surface of the tongue or shank 22.

The connection assembly at 17 may be connected to the body portion 14 in any suitable manner. For example, I show the channel portion 20 provided with a ferrule portion 42 engaging over the projection 43 and provided with a threaded lug 44 engaging the screw 45 carried by the body portion. Preferably the lug 44 and the body portion 50 have contacting inclined surfaces 46 and 47, respectively, tending to move the channel member 20 rearwardly when the screw 45 is tightened, whereby close contact is made between the rear end of the channel member 55 and the adjacent end of the strip 48.

The ferrule 42 of the channel member has bottom portions 50 branching from the main body of the channel member 20 and having inclined edges 51 and 52 and the ferrule 30 has a rearward projection 53 having edges 54 arranged adjacent to the edges 51. The inclination of the edges is toward the nut end of the bow, whereby catching of strings on short down strokes is minimized.

As already pointed out, the body portion

14 is preferably made of plastic material such as rubber in order that a frog may be readily shaped to fit a stick. This avoids the necessity of carrying a stock of frogs having varying sized and shaped stick-fitting concavities, 70 as a frog may have its concavity readily reshaped to fit a stick, it being merely necessary to apply heat locally to the concave portion to render it somewhat plastic whereupon it may be readily reshaped to fit the 75 stick. Furthermore, the body portion may be readily molded with the recesses therein and metallic parts may be readily connected thereto during molding.

From the foregoing, it will be apparent that 80 the tongue member may turn in the channel against the resistance of the spring 27 and that the latter returns the tongue member to normal position. This makes possible the bearing of one edge of the hair band on strings on light strokes and tilting thereof to bear evenly upon the application of greater pressure.

While I have shown my invention in but 90 one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. The combination with a bow having a hair band and a frog, of means connecting a 100 hair band to the frog including a member connected to the hair band, and spring means resisting turning of the member.

2. The combination with a bow having a hair band and a frog, of means connecting a 105 hair band to the frog including a member connected to the hair band, means for connecting the member to the frog and providing for relative turning movements thereof, and means for resisting such relative turning 110 movements and effective to return the member and frog to normal relative positions.

3. The combination with a bow having a hair band and a frog, of means connecting the hair band to the frog including a member 115 connected to the hair band and being elongated in cross section and spring means bearing on said member to resist turning movements thereof.

4. The combination with a bow having a hair band and a frog, of means connecting the hair band to the frog including a member connected to the hair band and means for connecting the member to the frog and including resilient means resisting relative turning 125 movements of the member and frog and effective to return the latter to normal relative positions thereof.

5. The combination with a bow having a hair band and a frog, of means connecting 130

the hair band to the frog including a member connected to the frog and provided with a channel, an elongated flat tongue connected to the hair band and arranged flatwise in the channel, means for connecting the tongue to the frog, and means for yieldably resisting turning of the tongue in the channel.

6. The combination with a bow having a hair band and a frog, of means connecting the hair band to the frog including a channel member connected to the frog; a tongue connected to the hair band and arranged in the channel; a lug on the tongue; and a spring connected to the frog, engaging over the lug to connect the tongue to the frog, and bearing against the tongue to yieldably resist turning thereof in the channel.

7. The combination with a bow having a hair band and a frog, of means for connecting the hair band to the frog including a tongue having portions off-set approximately the thickness of the hair band, means for connecting the hair band to one of said portions, means for connecting the other portion to the frog, and means providing for yieldably resisted turning movement of the tongue.

8. The combination with a bow having a hair band and a frog, of means for connecting the hair band to the frog including a member having a cross bar and a tongue portion connected to the cross bar, a ferrule for gripping the hair band with respect to the cross bar, means including a lug on the tongue portion for connecting said member to the frog, and spring means cooperating with the tongue portion to resist turning movement of said member.

9. The combination with a bow having a hair band and a frog, of means for connecting the hair band to the frog including a member, a ferrule engaging a portion of the frog and having bottom portions which are integral with the member, said bottom portions having side edges inclined toward the hair band, a tongue, means for connecting the hair band to the tongue including a ferrule having bottom edges adjacent to the first ferrule inclined toward the hair band, and means for connecting the tongue to the frog and providing for relative turning thereof.

10. A device for connecting a bow hair band to a frog including a body member, a hair band tongue connected to the body member so as to be capable of tilting movement about a longitudinal axis, and resilient means for resisting such tilting movement and effective to return the hair band to normal position relative to the body member.

11. A device for connecting a bow hair band to a frog including a body member, a hair band tongue, and a detachable connection between the body member and the tongue and including spring means for yieldably

resisting relative turning of the tongue and member.

12. A device for connecting a bow hair band to a frog including a body member having a channel, a hair band tongue fitting the channel, a lug on the tongue, and a spring connected to the body member, engaging over the lug and bearing against the tongue.

13. A frog for a violin bow comprising a body member having a concave groove adapted to fit a bow stick, at least that portion of said member provided with the groove being deformable by being rendered plastic by the application of heat in order to fit a stick, a member adapted for connection to a hair band, and means for connecting the frog to the last-named member so that the latter may move angularly.

14. A frog for a violin bow comprising a body member having a concave groove adapted to fit a bow stick, at least that portion of said member provided with the groove being made of material deformable by being rendered plastic by the application of heat to fit a stick, a member connected to the body member and providing a channel internally thereof, a tongue adapted to be connected to the hair band and fitting said channel, means for connecting the tongue to the body member, and spring means for resisting turning of the tongue in the channel.

In testimony whereof, I have hereunto subscribed my name this 14th day of June, 1929.

CHARLES B. GRAY.
